RESETTING MECHANISM FOR WEFT
REPLENISHING LOOMSRichard G. Turner, Worcester, Mass., assignor to
Crompton & Knowles Loom Works, Worcester,
Mass., a corporation of Massachusetts

Application September 11, 1939, Serial No. 294,313

5 Claims. (Cl. 139—231)

This invention relates to improvements in resetting mechanism for weft replenishing looms and it is the general object of the invention to cancel an initiated replenishing operation when the loom stops because of weft failure.

In the usual weft replenishing loom there will be some part which is moved from its normal position to an abnormal or indicating position when the weft detector initiates or calls for a replenishing operation by indicating exhaustion of weft in the weaving shuttle. When this part, which may be termed a controller, is in its abnormal or indicating position replenishment by an automatic action of the loom, or at least 10 an attempt at replenishment, will be a necessary result of continued loom operation.

If the filling breaks or becomes exhausted in the interval between indication of weft exhaustion by the detector and a replenishing operation 20 the loom will stop with the controller in indicating position. Under these conditions it is common practice for the weaver to remove the broken pick of filling and also place a fresh supply of weft in the shuttle, thereby making 25 an automatic replenishment not only unnecessary but undesirable. Upon resumption of weaving, however, the controller which is still being in indicating position will cause an automatic replenishment of weft and the fresh supply 30 placed into the shuttle manually by the weaver will be discarded. The supply of weft thus discarded may be injured by its contact with the bobbin can if the loom be the bobbin changing type, but in any event it must again be handled 35 before it can enter into active weaving.

It is an important object of my present invention to prevent the discarding of the manually replenished weft by cancelling an initiated transfer should the loom be stopped by the weft fork 40 while the controller is in indicating position. The control for accomplishing this result is derived from the weft stop motion and acts to return the controller to its normal non-indicating position whenever the loom is stopped by weft 45 failure. In this way the automatic replenishment is cancelled and the manually replenished weft remains in action.

The general features of my invention are applicable to bobbin changing and shuttle changing looms alike and I do not wish to be limited 50 in the use of my invention to bobbin changing looms. As a matter of convenience I have shown the invention applied to a bobbin changing loom having a controller of the type extensively used 55 in shuttle changing looms of the kind illustrated for example in Patents Nos. 2,054,174 and 2,054,192.

The condition already described will exist in 60 a loom operating with a single type of weft as well as in those looms which weave different

types of weft. I have illustrated my invention in connection with a multicolor weft replenishing loom, but certain features of my invention are not limited to looms of this type, inasmuch as the steps of indicating weft exhaustion, initiating a replenishing operation by movement of the controller to indicating position, and weft breakage with subsequent cancellation of the replenishing operation can all occur during the weaving of a block of single color in the pattern 10 of the fabric being woven.

Weft stop motions are customarily of two types one of which employs a slide located at one side of the cloth and carrying a fork to detect the weft extending from the selvage into the shuttle box every other loom beat, while the other type employs a fork mounted on the lay and located between the selvages to detect the presence or absence of weft on each beat of the loom. I have shown my invention in connection with 20 the latter type of stop motion, called commonly the center filling stop motion, but I do not wish necessarily to be limited to a weft stop motion of that type. It is sufficient if the stopping movement of some part of the weft stop motion 25 is communicated to the resetter for the aforesaid controller.

With these and other objects in view which will appear as the description proceeds, my invention resides in the combination and arrangement of parts hereinafter described.

In the accompanying drawings, wherein a convenient embodiment of my invention is set forth:

Fig. 1 is an end elevation of a weft replenishing loom having my invention applied thereto, parts being in section.

Fig. 2 is a plan view of a part of the loom taken in the direction of arrow 2, Fig. 1, parts being in section.

Fig. 3 is a vertical section on an enlarged scale 40 on line 3—3 Fig. 1, showing the indication storing controllers which are reset by operation of my present invention.

Fig. 4 is a detailed view on an enlarged scale 45 of a part of the structure shown near the center of Fig. 1, parts being in section.

Fig. 5 is a vertical section on an enlarged scale on line 5—5 of Fig. 2, and

Fig. 6 is a perspective view of a part of the 50 weft stop motion mounted on the loom breast beam and looking forwardly from the lay.

Referring particularly to Fig. 1, I have shown a loom frame 10 having a lay 11 mounted on a sword 12 supported by and turning around rocker 55 shaft 13 near the bottom of the loom. A connector 14 extends rearwardly from the lay and is connected to wrist pin 15 on the top shaft 16 which makes a revolution every pick of the loom.

The loom operates with two weaving shuttles one of which is shown at S, and the lay has two shifting shuttle boxes not shown at the end of the lay opposite that shown in Fig. 1. The 5 shuttle S carries a bobbin B to cooperate with a weft detector D located at the magazine side of the loom and acting electrically in the present instance to energize a solenoid 17 when the weft on the bobbin B is exhausted and the active 10 shuttle is on the replenishing side of the loom. Energization of the solenoid may be effected by means of a source of electric power P which is connected to the detector by wire 18 and to the solenoid by wire 19, while the detector is connected to the solenoid by wire 20. When weft 15 exhaustion occurs in the shuttle the electric circuit indicated in Fig. 1 will be closed to lift the core 21 of the solenoid and thereby elevate a lifting arm 22, see Fig. 3. A carriage 25 is 20 ably mounted on fixed pins 26 and is provided with two controller fingers 27 and 28, respectively, connected to yielding positioning elements 29 which in the present instance may be spring 25 plungers carried by the carriage. Each controller finger carries a trip 30 adapted for cooperation one at a time with the lifting arm 22.

The position of the trips with respect to the lifting arm is determined by the mechanism shown at the bottom of Fig. 1, where a cable 31 30 is attached to the lower end of an indicator lever 32 pivoted about a fixed axis 33. The cable 31 extends to the other side of the loom and is attached by connections not shown either to the drop boxes or some part moving in timed relation with them. The cable therefore acts to rock the lever 32 in a clockwise direction as viewed in Fig. 1 and a spring 34 rocks the lever in a counter-clockwise direction when the cable is slackened. A connector rod 35 extends from the lever 32 to the carriage 25 and is the means 40 by which the latter slides in response to shifting of the shuttle boxes to place one or the other of the strips 30 over the lifter arm 22. Energization of the solenoid will therefore 45 cause the lifter arm to engage the trip of the controller finger corresponding to the active exhausted shuttle.

A cam 37 rotating once every two picks of the loom rocks a lever 38 swinging about a fixed 50 pivot 39 and a lifter dog 40 pivoted to the forward, or left end of lever 38 as viewed in Fig. 1, is adapted for engagement with a normally stationary operating lever 41. The latter is connected by rod 42 to transfer latch 43 and shuttle 55 feeler 44. The latch 43 is connected to the usual transfrer arm 45, while the shuttle feeler is carried by supporting arm 46 and is swung rearwardly, or to the right as viewed in Fig. 1, when a transfer is about to occur.

A magazine designated generally at M supplies two different types of bobbins or weft carriers W and W' corresponding to the two weaving shuttles mentioned. The magazine is rocked by the connections indicated in Fig. 1 so that 65 the reserve bobbin under the transfrer arm corresponds to the active shuttle. Each shuttle will remain active for two picks or a multiple thereof and the alternation of activity on the part of the shuttles is controlled by a pattern 70 mechanism not shown and is accompanied by a shifting of the carriage 25.

The loom has a shipper handle 50 to operate a lever 51 attached to a rearwardly extending rod 52 which operates the shipping mechanism 75 not shown for the loom. This mechanism is

well understood, left hand motion of the shipper handle as viewed in Fig. 1 corresponding to a forward pull of rod 52 to cause the loom to operate. The shipper handle is mounted on shipper rod 53 and rocking of the latter in a right hand direction as viewed in Fig. 1 from normal running position will effect loom stoppage. 5

It is not deemed necessary to give a full description of the operation of the replenishing mechanism or the shipper control since these parts are already known and are shown for instance in my prior Patent No. 2,128,974. It is thought sufficient for present purposes to state that both the controller fingers illustrated particularly in Fig. 3 will be normally in the down position occupied by finger 28 of that figure and that when indication of weft exhaustion is given by the detector the lifter arm 22 will raise the controller finger corresponding to the active 15 shuttle to the position occupied by finger 27 in Fig. 3. Furthermore, the controllers are movable toward and from active position relatively to the lifter arm 22 by rocking of lever 32 in response to shifting of the drop boxes. The 20 details of the structure shown in Fig. 3 are set forth and described in the aforementioned Patent No. 2,054,192. When either of the controller 25 fingers 27 or 28 is raised a replenishing operation has been initiated and when the exhausted shuttle again moves toward the magazine end of the loom the controller finger corresponding thereto will be in a position to direct the lifting dog 40 into lifting relationship with respect to lever 41, see Fig. 3, whereupon the latch 43 will 30 be set for transfer and the shuttle feeler 44 placed for detecting the position of the shuttle 35 along the lay.

As already stated the present invention relates to means to reset the fingers 27 and 28, and 40 more generally the indication storing mechanism of a weft replenishing loom, when the weft stop motion stops the loom due to failure of weft. It is well known that the various types 45 of filling stop motions employed at the present time include in their construction a part which is moved upon weft failure to effect loom stopping. In the present instance I have elected to illustrate my invention in connection with a center stop motion of the type generally employed on silk looms, but I do not wish to be limited in the practice of my invention to this 50 particular kind of weft stop motion.

In the application of my invention of the structure already described it is convenient to 55 use certain parts which are shown in my co-pending application Serial No. 225,607. Since the structure shown in that application is used with my present invention I prefer to illustrate the transfrer arm which is the subject matter of the co-pending application, since it provides the normal means for resetting the controllers after a transfer. I wish it to be understood however that the present invention can operate independently of the structure shown in 60 65 the co-pending application.

As a convenient mounting for certain parts to be described I use a lever 90 pivoted to the loom frame at 91 and having a roll 92 for cooperation with an inclined plate 93 which moves with the transfrer arm 45. The lever 90 is normally held raised by a light spring 98 and is depressed when the transfrer arm is lowered. This last feature is not essential in my present invention, but I do employ a depending rod 100 pivoted to 70 75

the lever 90 at 101 and having a turn-buckle 102 as set forth in the co-pending application to reset the active controller 27 or 28 at the time of a normal transfer. A tube 103 depends from the 5 turn-buckle and has a stop collar 104 for engagement with the under side of a guide 105 through which the tube extends. The part 103 is made tubular herein for a purpose to be set forth but it can be considered as a continuation of rod 100 10 for the resetting purposes just described and it is to be understood that the tube 103 will be held normally in its raised position shown in Fig. 1 at all times except during a transferring operation of the loom.

15 In carrying my invention into effect I provide mechanism which will cause a resetting of an active controller finger in indicating position corresponding to an active shuttle the thread of which breaks or becomes exhausted during weaving with resultant loom stoppage through the weft stop motion. In this way the weaver can replenish the shuttle by hand without danger of a repeated automatic replenishment to be effected by the loom after weaving is resumed.

20 25 The type of weft stop motion illustrated is that customarily located near the center of the lay to detect the weft on every forward beat of the loom. These mechanisms are so well understood that I will describe such parts only as are necessary to an understanding of my invention. Further description will be found in Patent No. 2,141,656 to Adams to which reference may be made for the details of the weft stop mechanism.

30 Referring to Fig. 5 I have shown the lay as 35 provided with a dagger 110 the vertical position of which is controlled by the weft on the forward beat of the loom. If weft is present the fork 111 will be supported and the dagger will be in the relatively low position shown in dotted lines, but 40 if weft is absent or broken the fork falls into the well 112 in the lay and the dagger will be raised to the full line position of Fig. 5, as the lay moves forwardly or in the direction of arrow a. The breast beam 113 of the loom has supported on 45 the under side thereof a rolling rod 114 which rocks in bearings one of which is indicated at 115 and has secured thereto a dog 116 having a notch 117 positioned for engagement with the dagger 110 when the latter is raised. A cam arm 50 118 secured to the rolling rod 114 engages a second arm 119 on the shipper rod 53 to press the latter down and rock the shipper rod to stop the loom when the dagger enters the notch. Parts of the weft stop motion not essential to an 55 understanding of the present invention are omitted but may be of usual construction.

60 A head 120 pivoted to the dog at 121 extends forwardly or to the left as viewed in Fig. 5 through a guide 122 supported by a hanger 123 depending from the breast beam and is attached to a wire 124. The wire extends through a tubular guide 125 which may be in the form of a closely coiled spring one end of which is carried by the hanger. The guide extends along the 65 under side of the breast beam as shown in Fig. 2 and then leads rearwardly and has the end thereof extended through the turnbuckle 102 and secured within the vertical tube 103 as by soldering or the like. Tube 103 corresponds to the 70 lower part of the two part rod set forth in my co-pending application Serial No. 225,607 and is made hollow in the present instance to receive the flexible guide 125. The wire 124 extends downwardly inside the tube 103 and is attached 75 to a plunger head 126 normally though not nec-

essarily located within the tube as shown in the lower part of Fig. 4.

Adjustment of the wire 124 with respect to the guide 125 is obtained at the weft stop motion by making the head 120 in two adjustable parts 5 as shown in Fig. 5.

Under normal conditions with the thread intact during weaving the dagger 110 will be depressed to the dotted position of Fig. 5 and will pass under the notch 117 during the forward 10 beat of the lay. When the filling breaks, however, the dagger will remain raised in a manner customary to center stop motions and will engage the dog 116 to move it forwardly or to the left as viewed in Fig. 5 to cause rocking of 15 shafts 114 and 53 to stop the loom. The center stop motion therefore performs its primary function of stopping the loom when the weft breaks, but when the dog moves forwardly the wire 124 is caused to slide through the flexible guide 125 20 with the result that the plunger head 123 is projected downwardly from its normal position or to the dotted lines indicated in Fig. 4. If at this time the finger or controller in active position immediately under the plunger 126 has previously been raised by indication of weft exhaustion 25 it will be depressed by the plunger and the replenishing mechanism will thereby be reset to normal condition, thus cancelling the transfer and preventing an automatic replenishment. 30

When the loom is stopped the weaver will correct the mispick caused by the broken or exhausted filling and will replenish the shuttle by hand, as is customary. Upon resumption of 35 weaving therefore there will be no coupling of levers 38 and 41 by dog 40 and the fresh hand replenished weft in the shuttle will remain in action. It is to be understood that the controller 27 or 28 which is depressed by the plunger 126 corresponds to the active shuttle and the filling 40 stop motion does not act to reset a controller finger in indicating position but moved out of active position because its corresponding exhausted shuttle is temporarily idle.

45 It will be understood that projection of the plunger 126 is independent of motion on the part of tube 103 and can and ordinarily will occur when the latter is stationary. If the brake of the loom is loose so that the lay can reach front center position before stopping, a transfer will 50 occur and tube 103 will descend as well as plunger 123. The weaver however will notice that automatic replenishment has already taken place and that it is unnecessary to replenish the shuttle by hand. 55

60 From the foregoing it will be seen that I have provided mechanism for resetting whichever of the controllers 27 and 28 happen to be in active indicating position when the loom is stopped through the weft stop motion. It will be noted also that the tube 103 which is depressed by action of the transfer arm to reset the controller fingers under normal transfer conditions is also a carrier for the resetting device controlled by the 65 weft stop motion. Furthermore, while I have illustrated my invention in connection with a so-called center stop motion, I do not necessarily wish to be limited to motions of this type, inasmuch as other forms of filling stop motions have 70 a part which is moved to effect loom stoppage to which the wire 124 could be attached. Again, the invention is useful on looms operating with one or more weaving shuttles and is also applicable to shuttle changing looms which employ 75

the controllers 27 and 28 or parts similar to them.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a reserve bobbin to be transferred into a weaving shuttle, transfer mechanism effective when set for transfer to move the reserve bobbin into the weaving shuttle during a replenishing operation, means to initiate a replenishing operation of the loom upon occurrence of weft exhaustion in the weaving shuttle, a controller to be moved from normal to indicating position by the initiating means, an actuator having an operating stroke at two-pick intervals during the loom operation, coupling means controlled by the controller when the latter is in indicating position to couple the actuator to the transfer mechanism and set the latter for transfer, means to hold the controller in indicating position after the transfer mechanism is set for transfer, a weft stop motion to stop the loom upon failure of the thread in the weaving shuttle occurring subsequent to movement of the controller to indicating position and prior to operation of the coupling means, and connections between the filling stop motion and the controller to require the latter to move into normal position ineffective to couple the actuator with the transfer mechanism when the loom is stopped by failure of the weft.
2. In a multicolor weft replenishing loom having two reserve bobbins and operating with two weaving shuttles each of which may become active, transfer mechanism effective upon a complete operation thereof to insert either of the reserve bobbins into the weaving shuttle corresponding thereto, a pair of controllers for the transfer mechanism, one for each weaving shuttle, and each controller movable from normal to indicating position upon exhaustion of weft in the active shuttle corresponding thereto, means to move each controller into and out of active position, the controller in active position corresponding to the active shuttle, means controlled by either controller when in indicating position and also in active position to set the transfer mechanism at a given point in each two-pick cycle of the loom for a transferring operation, means to hold the controller in indicating position after the transfer mechanism is set for transfer, a weft stop motion operating to stop the loom upon failure of the weft thread of either shuttle when active, and resetting means operated by the weft stop motion and acting to move the controller in active position and corresponding to the active depleted weaving shuttle from indicating to normal position when the weft stop motion operates to stop the loom.
3. In a multicolor weft replenishing loom operating with two weaving weft supplies either of which may become active, weft replenishing mechanism to supply reserve wefts corresponding to the weaving weft supplies, a pair of controllers for the weft replenishing mechanism each movable from normal to indicating position upon occurrence of weft exhaustion in the active weaving weft supply corresponding thereto, means to move each controller into and out of active posi-

tion, the controller in active position corresponding to the active weft supply, means controlled by either controller when in active and indicating position to set the replenishing mechanism for a transferring operation which replaces the active depleted weaving weft supply with a reserve weft supply corresponding thereto, means to hold the controller in indicating position after the transfer mechanism is set for transfer, a weft stop motion to stop the loom upon failure of the weft of either of the weaving weft supplies, and resetting means for the controller in active position operated by the weft stop motion when the latter stops the loom to return a controller in the active and also in indicating position to normal position to prevent operation of the weft replenishing mechanism.

4. In a multicolor weft replenishing loom operating with two weaving shuttles either of which may become active, multicolor weft replenishing mechanism to supply two types of reserve weft, one type for each weaving shuttle, setting means movable from normal to indicating position to set the replenishing mechanism for a replenishing operation with respect to the reserve weft corresponding to the active shuttle when the latter is exhausted, subsequently acting means controlled by the setting means when in indicating position to complete the replenishing operation of the replenishing mechanism, means to hold the setting means in indicating position after the replenishing mechanism is set for a replenishing operation, a weft stop motion to stop the loom upon failure of the weft of either weaving shuttle when active occurring between the times of operations of the setting means and said subsequently acting means, and preventer means controlled by the weft stop motion to return the setting means to normal position and prevent operation of the subsequently acting means when the weft stop motion stops the loom.

5. In a multicolor weft replenishing loom operating with a pair of weaving shuttles either of which may become active, multicolor weft replenishing mechanism to supply reserve wefts corresponding to the weft supplies of the weaving shuttles, a controller for the weft replenishing mechanism corresponding to each weaving shuttle, means to move the controllers into and out of active position, the controller in active position corresponding to the active shuttle, means operative upon exhaustion of weft in the active shuttle to move the controller corresponding thereto in active position from normal to indicating position, a controller in indicating position capable of moving out of active position when the weaving shuttle corresponding thereto becomes inactive, means controlled by a controller in indicating and also active position to set the replenishing mechanism for a replenishing operation, means to hold the controller in indicating position after the transfer mechanism is set for transfer, a weft stop motion to stop the loom upon failure of weft in either weaving shuttle when active, and means operated by the weft stop motion when the latter stops the loom to return the controller in indicating position and in the active position only from indicating to normal position to prevent an operating of the weft replenishing mechanism.

RICHARD G. TURNER.
